UNITED STATES PATENT OFFICE

EDWARD J. McDONNELL, OF GROVETON, NEW HAMPSHIRE

FOURDRINIER MACHINE

Application filed December 20, 1930. Serial No. 503,722.

The invention relates to Fourdrinier machines and especially to that portion of the machine having the paper-making wire which is subjected to shake.

In the formation of paper on the Fourdrinier wire or paper-making wire subjected to a wire shake, the interlacing of the fibres takes place while the fibres are held in suspension in water, and in securing a well formed paper it is always desirable to keep the fibres under the influence of the wire shake when in suspension in the water as far down the wire as possible before the felting takes place, for otherwise a poorly formed sheet of paper is obtained.

Stock varies in its capability of retaining water. Hydrated stock in which the fibres have been well beaten in the beating engines possess properties by which they will retain the water and carry it well down the wire before the water is discharged. On the other hand, non-hydrated stock, which has been subjected to but little or no beating in the beating engines, as for example stock for making blotting, saturating and absorbent papers, will not retain the water, but discharge it so freely as to make it practically impossible to obtain a well formed sheet of paper owing to the limited period within which the fibres have been subjected to the wire shake.

Heretofore with fibres which freely discharge the water it has been common practice to add additional water to the stock going onto the wire in an effort to have the water carry the fibres further down the wire while under the influence of the wire shake, but this is objectionable for the reason that it exerts such disturbing influence as to make waves and currents causing an uneven stock formation, which is very undesirable.

The object of the invention is to provide means whereby the fibres will carry, when suspended in water, a sufficient distance down the wire to obtain a proper sheet formation, and this without the addition of water to the normal stock.

The invention can best be seen and understood by reference to the drawings in which such portion of a Fourdrinier machine is

shown as is necessary to a proper understanding of the invention, and in which—

Figure 1 is a plan of the mechanism to which the invention pertains.

Fig. 2 is a section on the line 2—2 of Fig. 1.

Fig. 3 is a section on the line 3—3 of Fig. 2.

Fig. 4 is a plan of a modified detail of construction, and

Fig. 5 is a section on the line 5—5 of Fig. 4.

Referring to the drawings:

1 represents the Fourdrinier wire or paper-making wire; 2 the breast roll around which the wire passes, and 3 rolls assisting in the support of the wire which is otherwise supported, driven, and shaken in the usual manner. 4 is a portion of one of the suction boxes. 5 is a plate over which the stock is directed to flow onto the wire, and 6 the splice.

The invention, as will now be explained, pertains to a means for preventing, limiting or otherwise controlling the drainage of water from the stock within that portion of the running wire lying between the point where the stock is first discharged onto the wire and the suction boxes. Arranged beneath this portion of the wire is a line of boards 7, parallelly arranged, with extension crosswise the wire, and all combining to form an extended table. The boards are preferably rectangular in form and in practice are of wood, maple being preferred. The wire slides over the top surfaces of these boards and when the boards are moved together with abutting edges, water is prevented from draining through the wire and is retained in the stock. Accordingly the fibres remain in water suspension and are subjected to the influence of the wire shake. By varying the distance by which the boards are separated from one another the discharge of water from the stock may be controlled.

Thus the fibres in the stock may be carried down the wire for any determinate length of carry, and the fibres remain in suspension, the water being gradually drained away as may be desired.

The boards 7 are supported and adjustably controlled with relation to one another in the

following manner: Secured to bars 8 extending along either side of the machine are hangers 9 supporting side rails 10. The boards are supported by, and adjustable on these side rails. Each of the boards is borne by a preferably T-shaped metal carrier 11 of which 12 represents the head of the carrier to which the board is secured, and 13 its shank. The head of the carrier is extended at either end beyond the shank and secured to these projecting ends of the head are blocks 14 which project downward alongside the ends of the shank and rest upon the side rails 10, being slidable thereon. For preventing endwise displacement of the boards and carriers the shanks of the carriers are preferably of sufficient length to extend below the top edge of the side rails and lie between these rails.

For securing the adjustment of the boards with relation to one another there is secured to the top surface of the side rails just outside the blocks 14 racks 15. These racks will assist in preventing lateral displacement of the boards and their carriers by the bearing of the blocks 14 against the racks. Traveling on the racks 15, respectively, are toothed wheels 16. The wheels are borne by a common connecting axle rod 17 to which the wheels are fixedly secured. These rods pass loosely through eyes 18 secured to the ends of the block. Accordingly as the toothed wheels are moved on the racks the carriers and boards carried by them will be adjusted with relation to one another and moved into abutting contact, closing all space between them, or to any graduated separation depending upon the positioning of the wheels. The set of wheels 16 for each board are turned by extending their connecting rod 17 beyond the wheels to which the rod is secured. The ends 19 of the rod so extended are squared or otherwise fitted to receive a tool or key 20 by which the set of wheels are turned and by such turning adjustably positioning the board. Access is had to the ends of the rod through the hangers 9 by means of openings 21 in the hangers.

In Figs. 4 and 5 a modified arrangement is shown in that rolls 20 are employed in place of boards. Blocks 14' are employed resting and slidable upon the wire the same as the blocks 14 in the construction first described. The rolls are arranged to turn by any suitable ball bearing connection (not shown) on rods 23 extending through the rolls, and the ends of these rods rest in slots 24 cut in the tops of the blocks. The blocks together with the rolls borne by them are adjustably positioned the same as the boards in the construction first described. Practice has demonstrated that rolls are not so effective as boards. While the water will fill the spaces between the rolls and so prevent further water drainage through the wire, especially when the

rolls are in contact or very slightly out of contact, yet the turning of the rolls tends to produce a slight agitation in the water which is transmitted to the stock and is objectionable on this account. When boards are used the stock is subjected to no such disturbing influence.

The members thus arranged beneath the running wire may have extension to any determinate distance in the direction of the suction boxes as may be desired. In practice boards about 8 inches wide are used and these boards together extend beneath the running wire a distance falling short of the suction boxes, the remaining space being taken up by ordinary rolls which assist in the support of the wire. With the Fourdrinier wire having a running space of seventy feet between the point where the stock is first fed onto the wire and the suction boxes eight 8 inch boards will generally be found sufficient, although practice will better demonstrate the number of boards to be employed.

Having thus fully described my invention, I claim and desire to secure by Letters Patent of the United States:—

1. In a Fourdrinier machine having a paper-making wire, the combination therewith of a series of members arranged to form an extended table beneath the wire and over which the wire passes, said members forming the table being adjustable with relation to one another to either close or leave a determinate opening between adjacent ones of said members forming the table whereby the discharge of water from the stock after its entry onto the wire will be controlled, and means for adjustably positioning said members.

2. In a Fourdrinier machine having a paper-making wire, the combination therewith of a series of boards arranged to form an extended table beneath the wire and over which the wire passes, said boards being adjustable to either close or leave a determinate opening between adjacent ones of said boards whereby the discharge of water from said stock after entry onto the wire will be controlled, and means for adjustably positioning said boards.

3. In a Fourdrinier machine having a paper-making wire, the combination therewith of a series of rolls arranged to form an extended table beneath the wire and over which the wire passes, said rolls being adjustable to either close or leave a determinate opening between adjacent ones of said rolls whereby the discharge of water from said stock after entry onto the wire will be controlled, and means for adjustably positioning said rolls.

4. In a Fourdrinier machine having a paper-making wire, the combination therewith of a series of members arranged beneath the wire and adjustable to either close

or leave a determinate opening between adjacent ones of said members whereby the discharge of water from the stock after its entry onto the wire will be controlled, and
5 means for adjustably positioning said members comprising rails supported to extend along the sides of the machine, racks on said rails, toothed wheels traveling on said racks in sets corresponding with the number of said
10 members, and means connecting said sets of wheels to the individual members whereby said members will be adjustably positioned with relation to one another as the wheels are turned.

15 EDWARD J. McDONNELL.
